UNITED STATES PATENT OFFICE.

FLORIAN BUSCH, OF NEW YORK, N. Y.

GAS-STOVE.

SPECIFICATION forming part of Letters Patent No. 629,150, dated July 18, 1899.

Application filed March 15, 1899. Serial No. 709,168. (No model.)

To all whom it may concern:

Be it known that I, FLORIAN BUSCH, a citizen of the United States, residing in the city of New York, in the borough of Manhattan and State of New York, have invented certain new and useful Improvements in Gas-Stoves, of which the following is a specification.

This invention relates to an improved gas-stove which can be used either in connection with an ordinary gas-bracket or in connection with a separate stand, said stove combining the advantages of simultaneously heating and illuminating the room in which the stove is placed; and the invention consists in the combination, with a Bunsen burner, of a suitable support for the same, a heat-radiating shell supported above said Bunsen burner, an incandescent mantle, said mantle being provided with a flame-opening of approximately the same size as the flame-opening of its burner, and means for supporting said mantle in position on the Bunsen burner, as will be more fully described hereinafter and finally pointed out in the claim.

In the accompanying drawings, Figure 1 represents a side elevation of a gas-bracket with my improved gas-stove supported thereon with the regular Welsbach or other burner removed from the bracket. Fig. 2 is a front elevation of a gas-bracket with my improved gas-stove having a plurality of Bunsen burners. Fig. 3 is a front elevation of a number of gas-stoves on the same gas-supply pipe, to be used as a heater in restaurants, &c. Fig. 4 is a front elevation, partly in vertical transverse section, of my improved gas-stove supported on a separate stand and drawn on a larger scale; and Fig. 5 is a plan of the construction shown in Fig. 4 with the top plate or cover removed.

Similar letters of reference indicate corresponding parts.

Referring to the drawings, A represents a Bunsen burner of that kind which is usually used in the well-known Welsbach incandescent gas-burners. This Bunsen burner is provided with radial arms B, extending therefrom, said arms supporting a heat-radiating shell C, which is preferably provided with a flat top plate or cover C', that rests on the shell C, the shell having openings in its lower

part and transverse ribs α' for supporting the top plate or cover C'.

On the burner A is supported, by means of wires a , which rest at their ends on the heat-radiating shell and extend across the central opening of the same, an incandescent mantle A', which is, however, preferably made of shorter length than the ordinary incandescent mantles, so that a portion only of the gas burned in the Bunsen burner serves for heating the mantle to incandescence, while the remaining portion serves for heating the radiating-shell, so as to be utilized for heating the room or for cooking purposes. The mantle is not closed at its upper portion, as are the mantles in common use for lighting purposes; but, as shown in the drawings, the mantle is provided with a flame-opening of approximately the same size as the flame-opening of the burner, for permitting the free burning of the excess of gas not required for lighting. In this manner such a gas-stove can be used for heating and illuminating a room, such as a hall-room, bath-room, &c. The stove is so arranged that it may be supported on an ordinary gas-bracket D, after the Welsbach or other burner, with its cylinder and shade, is removed from the same, said Welsbach burner being supported in the meantime on a small separate stand, or the stove may be used in connection with a separate supporting-stand D', as shown in dotted lines in Figs. 1 and 2 and in full lines in Fig. 4, or a number of gas-stoves are supplied by the same gas-supply pipe D², as shown in Fig. 3, as in restaurants, &c., for heating dishes containing food. For larger rooms it is preferable to arrange in connection with the Bunsen burner A two or more additional burners A², preferably one at each side of the central burner, as shown in Figs. 2 and 4. The burners A' A² are arranged directly below opening d'd in the bottom of the shell c.

In this case the surplus heat of the central burner and the heat of the two side burners are used for heating the radiating-shell, which latter serves either for heating the room or for cooking purposes, as desired, while the incandescent mantle supplies necessary light.

The advantages of my improved gas-stove are that the heating and illuminating of rooms can be accomplished at the same time with a

considerable economy in gas. The same principle may be also applied to larger sizes of radiators, in which a number of individual heating and illuminating gas-stoves are combined and inclosed in a suitable ornamental casing for heating large rooms, parlors, greenhouses, &c.

Having thus described my invention, I claim as new and desire to secure by Letters

10 Patent—

The combination, with a Bunsen burner, of a suitable support for the same, a heat-radiating shell supported above said Bunsen

burner, an incandescent mantle, said mantle being provided with a flame-opening of approximately the same size as the flame-opening of its burner, and means for supporting said mantle in position on the Bunsen burner, substantially as set forth.

In testimony that I claim the foregoing as 20 my invention I have signed my name in presence of two subscribing witnesses.

FLORIAN BUSCH.
